METHOD OF AND APPARATUS FOR MAKING
KNITTED FABRICGeorge L. Logan, Syracuse, N. Y., assignor to
Tompkins Bros. Co., Syracuse, N. Y., a corpora-
tion of New York

Application July 6, 1937, Serial No. 152,213

9 Claims. (CL. 66—80)

This invention relates to knitted fabrics, and a method of and apparatus for making the same. More especially, it has to do with the utilization of a backing or lay-in thread or yarn to form 5 stitches which appear in a predetermined pattern on the face of the fabric.

A backing or lay-in thread normally and heretofore shows only on the back of the fabric, but through the practice of my invention, wherein 10 the backing thread is caused to appear on the face of the fabric at predetermined needles, as well as on the back of the fabric, I am able to obtain a contrast in the same feed or horizontal row of stitches as by using a backing or lay-in 15 thread or yarn of a distinguishing color or other characteristic.

An important advancement resulting from the invention resides in the ability to obtain a wide spacing of stripes or lines running through the 20 fabric vertically or at an angle to the horizontal, or, in fact, any desired spacing, without showing an intermingling of colors, and without necessitating a long float on the back of the fabric. For example, a backing or lay-in thread or yarn 25 of one color may be used to produce solid vertical or substantially vertical stripes or lines spaced as much as forty needles apart, more or less, and another thread or yarn of another color used to form a background between these vertical lines 30 or stripes, which background can also be of a solid color. Of course, the invention is not limited to the formation of vertical lines or stripes by the backing or lay-in thread or yarn, as the same may be knitted in the fabric so as to appear 35 on the face of the fabric as an inclined line or stripe, and the inclination thereof may be varied to any desired degree. Also, the background intermediate the stripes or lines formed by the lay- 40 in or backing thread or yarn may be composed 45 of threads or yarns of two or more colors, or of different or contrasting physical characteristics, so as to produce a mixed background rather than a background of a solid color, as mentioned above, if desired.

One practical and important application of my invention is found in the case of such designs as so-called overplaids. Heretofore, it has been considered impossible or impracticable to produce overplaid designs on flat fabrics. By way of explanation, a regular plaid is considered to be a design of vertical and horizontal stripes of one color, arranged to form squares or blocks of any size, with the inner portion of the squares or blocks bounded by the stripes showing the stripe 55 color and/or another color. This type of design

is not new in flat fabrics. However, for an overplaid, it is necessary to introduce still another color in the fabric in horizontal and vertical stripes or lines forming additional blocks or squares which are displaced both horizontally 5 and vertically with respect to the blocks or squares of the regular plaid design aforesaid; but it is important, or at least very desirable, that the color of the overplaid stripes or lines shall not show on the face of the fabric between the over- 10 plaid stripes or lines. I am now able to readily obtain such designs in flat fabrics, as will hereinafter more fully appear.

The primary object of the invention is to produce a knitted flat fabric having a backing or lay- 15 in thread or yarn incorporated therein in such manner that the same appears at predetermined spaced points on the face of the fabric, but not intermediate such points, and as a further ob- 20 ject, to provide an improved method of and appa- 25 ratus for so incorporating such a backing or lay-in thread or yarn to form a design, or a part of a design, on the face of the fabric.

Another object of the invention is to provide 25 in a circular spring needle knitting machine, means for introducing and manipulating a back- 30 ing or lay-in thread or yarn under the beards of selected needles to ultimately form a solid or un- 35 interrupted line or stripe on the face of the knit- 40 ed fabric, while on the same horizontal feed or row of stitches, all other needles except these selected needles receive under their beards an- 45 other thread, or yarn, which is knitted to form the main body of the fabric.

Other and further objects and advantages of 35 the invention will be hereinafter described and the novel features thereof defined by the appended claims.

In the drawings:

Figure 1 is a fragmentary view in top plan, 40 showing somewhat diagrammatically a portion of a needle circle of a leaded or trick spring needle circular knitting machine, and its associated yarn or thread manipulating instrumentalities, the same having an arrangement as in practicing my 45 invention as applied to knitting an overplaid de- sign;

Figure 1—A is a continuation of Figure 1;

Figures 2 and 2—A are developed views, shown 50 somewhat diagrammatically in side elevation, il- 55 lustrating the relationship of the various threads at the different points about the needle circle in the course of knitting one horizontal stitch row or feed in the production of a fabric having an overplaid design on the face thereof;

Figure 3 is an enlarged, fragmentary top plan view of the needle circle, showing the manner in which the lay-in or backing thread or yarn is initially presented to the needles;

5 Figure 4 is a somewhat diagrammatic view of a fragmentary portion of a knitted flat fabric illustrating the application of my invention to the knitting of an overplaid design.

10 Figure 5 is an enlarged view of a fragmentary section of fabric knitted according to my invention, and particularly showing the stitch structure, and the backing or lay-in thread knitted in such manner as to appear on the face of the fabric at predetermined needles only, thus forming 15 a vertical stripe at such points in the fabric as represented by the shaded stitches or loops.

15 Figures 6 to 12, inclusive, are detail sectional views taken on the lines 6—6, 7—7, 8—8, 9—9, 20 10—10, 11—11 and 12—12, respectively, of Figure 1—A, and showing the different steps of the knitting operations as they occur at the different points about the needle circle in the knitting of each horizontal row of stitches, as diagrammatically represented in Figure 2—A.

25 25 Like reference characters designate corresponding parts in the several figures of the drawings.

Considering first Figures 1 and 1—A, there is represented in these views a well known type of circular spring needle knitting machine which 30 includes the usual rotary needle cylinder (not shown) which carries the spring needles 1, together with a suitable set-up of wheels and equipment arranged so as to produce an overplaid in the knitted fabric, as shown in Figure 4.

35 The various thread feeding and manipulating wheels and equipment are for the most part conventional parts and are well known to those skilled in the art, but it will be observed that the same are arranged in a novel relationship so as 40 to produce the new result, to wit, an overplaid design, which I am able to now obtain on such a knitting machine. The fabric is knitted on the spring needles 1 in the usual tubular form, and as the stitches are cast off the needles, the fabric 45 is taken up axially, preferably in an upward direction, by the usual take-up means (not shown) which forms a part of the conventional knitting machine represented in the drawings.

The reference character 2 designates a conventional cloth push-down or shoe which is 50 mounted in relation to the needle circle as to push the previously knitted stitches or loops down on the needles as the needle circle, together with the knitted cloth, rotates in the direction of the 55 arrows shown in Figures 1 and 1—A. Intermediate the opposite ends of the push-down 2, there is mounted on the machine a backing wheel 3 which is adapted to introduce a backing or lay-in thread or yarn 4 into the needle circle. This 60 backing thread is represented in the drawings as being blue in color, by way of example, but, of course, I do not desire to be limited to the use of any particular color. In introducing the backing thread 4 into the needle circle, it is laid in the 65 usual manner, that is, alternately in front and back of selected needles. Preferably, the backing thread is alternately disposed in front of one needle and behind two needles, as best seen in Figure 3, but this arrangement may be varied as 70 desired. To obtain the initial disposition of the backing thread, as shown in Figure 3, blocks 3' are inserted in the backing wheel 3 at suitable points, so that these blocks will engage every third needle of the needle circle and push the same inwardly towards the axis of the needle 75

circle, thereby causing the backing thread to be brought down in front of every third needle. At those points where there are no blocks in the backing wheel, the backing thread will be fed in behind the needles. As the needles advance in the direction of the arrows beyond the backing wheel, the backing thread is carried down on the needles by the clearing wheel 5. Thereafter, another thread 6, which is represented in the drawings as a white thread, is put into the beards of the needles by the stitch wheel 7 at all needles except where it is desired to show the backing thread on the face of the fabric. It might be mentioned here that, as is usual in such knitting machines as represented herein, the back of the 10 fabric is on the outside of the knitted tube and the face of the fabric is on the inside.

15 The thread 6 is kept out of certain selected or designated needles by blocks 7' in the stitch wheel 7, which act to close the selected needle beards engaged thereby, and thus prevent the thread from entering under the beards. These blocks 7', which are inserted between the blades of the stitch wheel 7, must be set on one of the needles which is pressed in by a block 3' of the backing wheel 3, as will hereinafter become more apparent. According to the arrangement illustrated in the drawings, the blocks 7' of the stitch wheel 7 are disposed to engage every twenty-first needle, thereby causing the thread 6 to be left out of these needles, as best seen in Figure 2—A, at the point designated 8. At this same point, it will be noted that the backing thread 4 lies in front of this selected needle, that is, on the outside of the needle circle.

20 As the needles advance beyond the stitch wheel 7, they come into engagement with the presser 9, which presses all of the needle beards closed excepting at those points where there is a deep slot 9' in the presser. These deep slots 9' must be set on the same needle as the blocks 7' of the stitch wheel 7, which, as previously mentioned, engage every twenty-first needle. Thus, as the cloth is allowed to raise by the termination of the push-down 2, and by the raising action of the 25 lander burr 10, as the needles advance in the direction of the arrows, the old loops, together with the backing thread, are caused to slide up under the needle beards at the point 8'. At this point 8', the thread 6 is still left out of the 30 needle under the beard of which the backing thread and the old loop from the previous feed has just been received. These old loops are designated 11. The old loops 11 are not allowed to cast off at the point 8', but are pushed down 35 again by the push-down wheel 12, while the backing thread 4 is retained under the beard of the needle at this point. In only the predetermined, designated needles, which, according to the example given herein, are composed of every 40 twenty-first needle, is the backing thread under the needle beard, whereas the rest of the needles have the backing thread interwoven in back and in front of them in the regular manner.

45 As the needles advance beyond the push-down 45 wheel 12, they come into engagement with the presser 13 which now presses all the needle beards closed, and then the lander burr 14 lands the old loops 11 on the needle beards. Further advancement of the needles brings the same into position 50 where the cast off wheel 15 casts the old loops off the needles, thereby completing the knitting of a succession of loops. The manipulation of the threads and formation of the stitches or loops as just described is shown step-by-step in Figures 6 55

to 12, inclusive, wherein Figure 6 represents the step of initial introduction of the backing or lay-in thread, and Figure 12 represents the final formation of this backing or lay-in thread into a 5 stitch or loop at predetermined needles such as those at the points designated 8, 8', etc., of Figure 2—A. In the completed fabric, knitted in the manner just described, the backing thread 4, which has been illustrated as a blue thread, will 10 be presented at spaced points on the face of the fabric in the form of solid or continuous stripes or lines, designated 16 in Figures 4 and 5. The stripes or lines 16 are of a solid and uninterrupted blue color by reason of the fact that the white 15 thread 6 is floated on the back of the fabric, and lies behind the backing thread stripes at these points.

Referring now to Figure 1, S generally designates a striper which may be of any suitable construction, and the purpose of which is to introduce a thread of a third color into the fabric in carrying out the over plaid design shown in Figure 4. The striper includes a pair of fingers 17 and 18, each of which carries a separate thread so as 20 to alternately present the same to the stitch wheel 19, which is adapted to feed these threads into the needles, one at a time, in the usual manner. In the case of the fabric illustrated in Figure 4, one of these threads, for example, the thread 20, 25 is red in color, and the other thread 21 corresponds in color to the color of the backing thread, which has been shown as a blue thread. Of course, these colors may be varied as desired, according to the contrast preferred in the ultimate 30 design to be produced on the fabric. Through the interchangeable action of the striper fingers 17 and 18 of the striper S, in the usual and well known manner, vertically spaced blue stripes or lines 16', extending horizontally on the face of 35 the fabric, are produced. These horizontal blue stripes 16', together with the vertical blue stripes 16, form blocks or squares on the fabric, and constitute the overplaid stripes or lines. The regular plaid design is formed by the red and white 40 threads 21 and 6 respectively, which are knitted and striped in the fabric in the well known, conventional manner involving the use of a cut presser (not shown) ordinarily used for a tuck stitch pattern, and a striper additional to the one 45 shown in the drawings, to produce vertical white stripes or lines 22 and horizontal white stripes or lines 22', which, taken together, form blocks or squares on the face of the fabric which are displaced both vertically, as well as axially, respecting the blocks or squares formed by the horizontal 50 and vertical blue stripes. With the set-up as illustrated in Figures 1 and 1—A, the background color on the face of the fabric will be composed of a mixture of red and white threads, which 55 distinctly contrast with the various stripes, and present a very pleasing and attractive design.

It will be understood that Figures 1 and 1—A show only so much of the setup of the knitting machine as is essential to the knitting of the 60 backing or lay-in thread to form a part of a pattern on the face of the fabric. In the case of the over-plaid pattern shown in Figure 4, additional feeds are required, as will be obvious to those skilled in the art. In other words, the setup 65 shown in Figures 1 and 1—A would be duplicated on the opposite side of the machine to provide a striper diametrically opposed to striper S, and this other striper would feed red and white threads instead of red and blue, this being necessary to 70 produce the horizontal white stripes 22'. There

would also be another white thread fed diametrically opposite to the stitch wheel 7, and another blue backing or lay-in thread fed diametrically opposite to the backing wheel 3, these feeds being identical with those shown in the drawings. Accordingly, the regular stitches will be knitted in alternate red and white horizontal rows or courses when both stripers are feeding red threads. To produce a horizontal white stripe, the striper opposite to S is changed in the conventional manner 10 to render its red feed inoperative and its white feed operative for one course, thus producing three successive white courses which constitute one horizontal white stripe. Thereupon, the striper opposite to S is immediately changed from 15 a white feed to a red feed and the knitting is continued in alternate red and white courses until another horizontal white stripe is desired.

To get the vertical white stripe 22, the red threads are merely tucked behind the white at 20 these points in a conventional manner so that red is on the back of the fabric and only the white shows on the face.

As used in the spring needle knitting machine trade, the terms "backing thread" and "lay-in 25 thread" are synonymous, and they are so intended to be understood in the foregoing specification and appended claims.

From the foregoing, various modifications of my new method and apparatus to obtain different 30 striped or other designs will be readily apparent to those skilled in the art. Obviously, instead of obtaining the designs by the use of threads or yarns of contrasting colors, I can use threads or yarns of different physical characteristics. In 35 any case, one of the essential features of the invention is to produce a contrasting effect at spaced points on the face of the fabric through the use of a backing or lay-in thread or yarn which is so related to the knitted fabric body as 40 to appear at predetermined points on the face thereof, and which eliminates or obviates long floats.

While the specific details have been herein shown and described, the invention is not confined thereto as changes and alterations may be made without departing from the spirit thereof as defined by the appended claims.

Having thus described my invention, what I claim as new and desire to secure by Letters 50 Patent is:

1. The method of knitting flat fabrics on circular spring needle knitting machines, which comprises introducing a thread or yarn into all but certain spaced needles and knitting the same 55 to form a knitted body having floats at spaced points therein, and introducing a contrasting lay-in thread or yarn in the same horizontal row of stitches and knitting the same at the certain spaced needles aforesaid in such manner that the 60 latter thread or yarn appears on the face of the knitted body only at the spaced float points aforesaid.

2. The method of knitting flat fabrics on circular spring needle knitting machines, which 65 comprises introducing a thread or yarn into the needles to form a knitted body, introducing a contrasting lay-in thread or yarn in the same horizontal row of stitches, manipulating the threads or yarns so that the lay-in thread or yarn 70 is brought under the needle beards of selected needles while the first-mentioned thread or yarn is brought under the beards of all other needles of the same feed or horizontal stitch row except the selected needles aforesaid, and knitting the 75

threads to form a succession of loops, certain of which are composed of the lay-in thread or yarn and are presented at spaced intervals on the face of the fabric, with the first-mentioned thread floated on the back of the fabric at such points.

3. The method of knitting flat fabrics on circular spring needle knitting machines, which comprises introducing a thread or yarn into all but certain spaced needles and knitting the same to form a knitted body, and introducing a contrasting lay-in thread or yarn alternately in front of and behind the needles in the same horizontal row of stitches, and knitting said latter thread or yarn at the certain spaced needles aforesaid 10 in such manner that the latter thread or yarn appears on the face of the knitted body only at spaced intervals.

4. The method of producing designs in flat fabrics on circular spring needle knitting machines, which comprises introducing a thread of one color into the needles and knitting the same to form loops, pressing the loops down on the needles, introducing a lay-in thread of another color alternately in front of and behind the needles, moving the latter thread downwardly on the needles, introducing another thread of a third color under the beards of all of the needles except certain selected ones of those needles which have the lay-in thread in front of the same, pressing the beards of all of the needles closed excepting those certain selected needles aforesaid which do not have the thread of the third color under the beards, moving the lay-in thread and loops upwardly on the needles, whereby to bring the lay-in thread and certain of the loops under the needle beards of the selected needles aforesaid, pushing the loops down on the needles while leaving the lay-in thread under the needle beards of the selected needles, pressing all of the needle beards closed and landing the loops on the beards and casting the same off of the needles, and periodically substituting another thread of the same color as the lay-in thread, for the first-mentioned thread.

5. In a circular spring needle knitting machine of the class described, the combination with a rotary needle cylinder carrying a circle of bearded spring needles, of means for introducing a thread into all but certain spaced needles and knitting the same to form loops and spaced floats in the same horizontal row, and means for introducing a lay-in thread into the needles and for manipulating and knitting the same at the certain spaced needles aforesaid in such manner that the lay-in thread is presented on the face of the fabric only at the spaced floats aforesaid in the same horizontal row of loops.

6. In a circular spring needle knitting machine of the class described, the combination with a rotary needle cylinder carrying a circle of bearded spring needles, of means for introducing a thread into all but certain spaced needles and knitting the same to form loops and spaced floats in the same horizontal row, and means for introducing a lay-in thread into the needles and for knitting the same at the certain spaced needles aforesaid so that the lay-in thread is presented on the face

of the fabric at the spaced floats only, in the form of a continuous succession of knitted loops extending lengthwise of the fabric.

7. In a circular spring needle knitting machine of the class described, the combination with a rotary needle cylinder carrying a circle of bearded spring needles, of means for introducing a thread into the needles and knitting the same to form loops, means for introducing a lay-in thread into the needles and for manipulating the same in such manner that the lay-in thread is presented on the face of the fabric at spaced intervals, and means for floating the first-mentioned thread on the back of the fabric at those points where the lay-in thread is presented on the face of the fabric.

8. In a circular spring needle knitting machine of the class described, the combination with a rotary needle cylinder carrying a circle of bearded spring needles, of a stitch wheel including means for introducing a thread into all of the needles excepting certain selected needles, a backing wheel for introducing a lay-in thread alternately in front of and in back of the needles, with said lay-in thread disposed in front of the selected needles aforesaid, and instrumentalities for manipulating said threads so as to knit the lay-in thread at the selected needles aforesaid into loops, and to knit the other thread also into loops at the other needles, whereby to present the knitted lay-in thread loops on the face of the fabric at spaced intervals corresponding to the selected needles aforesaid, with the other thread floated on the back of said fabric at such points.

9. In a circular spring needle knitting machine of the class described, the combination with a rotary needle cylinder carrying a circle of bearded spring needles, of a stripper for alternately introducing threads of different colors into the needles, means for knitting said threads to form a succession of loops arranged in spaced stripes extending horizontally across the fabric, means for pressing down the loops on the needles, a lay-in wheel for introducing a lay-in thread of a color corresponding to one of the colors of the first-mentioned threads, into the same horizontal stitch row so as to be alternately disposed in front of and back of the needles, means for pushing down the lay-in thread on the needles, a stitch wheel for introducing a thread of another color into all but certain selected needles having the lay-in thread in front of the same same, a presser for pressing closed the beards of all the needles excepting those selected needles aforesaid, a lander burr for moving the loops and lay-in thread under the beards of the selected needles aforesaid, push-down means for pushing the loops down on the needles while the lay-in thread is retained under the beards of the selected needles aforesaid, presser means for pressing the beards of all the needles closed, lander means for landing the loops on the beards of all the needles, and a cast-off wheel for completing the knitting of a succession of loops, whereby to produce a design on the face of the knitted fabric having vertical stripes formed by the lay-in thread.

GEORGE L. LOGAN.
